Patented Mar. 10, 1925.

UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed March 26, 1924. Serial No. 701,988.

To all whom it may concern:

Be it known that I, GEORGE CLAUSING, a citizen of the United States, residing at Portsmouth, in the county of Scioto and State of Ohio, have invented certain new and useful Improvements in Lasts, of which the following is a specification, reference being had therein to the accompanying drawing.

10 My invention relates to lasts.

The object of my invention is to provide a last of simple and strong construction which will maintain its position in either expanded or collapsed condition.

15 In particular it is my object to provide a last in which the spring links may be more readily flexed by a system of levers in connection with the links.

Referring to the drawings:

20 Figure 1 is a section of the last showing the link and leverage arrangement when the last is in expanded position.

Figure 2 is a similar view of the last in its collapsed position.

25 Referring to the drawings in detail:

1 is the heel which has a substantially vertical forward face 2 and a rearwardly directed forward face 3, which is located at an angle to the vertical face and also at an angle to the rear vertical face 4 of the toe part 5. The heel part has a cutaway section 6 and the toe part has a cutaway portion 7 which are adjacent to one another, having their open ends communicating and also 30 communicating with the faces 3 and 4. A portion of the rear face 4 of the toe part adjoins and abuts the front face 2 of the heel part when the parts are in expanded position, while the faces 3 and 4 are in abutment 35 when the parts are in collapsed position.

40 Any form of hinged joint may be provided, but I prefer the semicircular projection 8 fitting into the corresponding semicircular depression 9. It is preferred that the periphery of this projection describe 45 more than an arc of 180 degrees.

45 Anchor pins 10 and 11 are transversely mounted in the toe and heel parts respectively. Upon these pins are mounted angular links or plates which consist of vertical 50 portions 12 and downwardly extending laterally directed portions 13. The free end of the portion 13 is riveted at 14 to the lower end of the portion 12 of the link or plate. 55 These links are made of steel and are some-

what resilient and by their arrangement a multiplication of force is secured through the leverage developed. The pins are so mounted that a line drawn between their centers is below the point about which the 60 points pivot when the parts are in expanded position. This line moves over this pivotal point or dead center, which is designated approximately 15, when the parts move to collapsed position.

65 When the parts pass over the dead center the links are flexed and the flexing is multiplied by the leverage secured. It will be obvious that the line between the centers of the pins 10 and 11 will tend to grow longer 70 when the parts pass over dead center and to compensate for this the links must yield. The lever portions 12 assist in this compensation.

I desire to comprehend within my invention such modifications as may be necessary to adapt it to varying conditions.

Having thus fully described my invention, what I claim as new and desire to secure by Letters Patent, is:

75 1. In a last, a toe part, a heel part, means permitting said parts to rock with respect to one another, pins mounted in the respective parts, links mounted on said pins, said links consisting of L-shaped bodies having substantially vertical portions and laterally and downwardly extending portions, the end of one laterally and downwardly extending portion being connected to the bottom of the other vertical portion.

80 2. In a last, a heel part, a toe part, and means permitting said parts to pivot with respect to one another, pins transversely mounted in said respective parts, links mounted on said pins, a portion of said links 85 extending downwardly from the pin on which it is mounted and another portion extending to a point adjacent the bottom of the other downwardly extending portion of the other link and fastened thereto.

90 3. In a last, a heel part, a toe part, means for pivoting said parts one on the other, means for connecting links to said parts, yielding links mounted on said connecting means, and means for attaching the free ends of said links to one another and maintaining said attached ends at points below said connecting means, whereby a spring lock is effected between the toe and heel 95 parts.

4. In a last, a heel part, and a toe part so arranged as to move with respect to one another from collapsed to expanded position and vice-versa, links connecting said parts, each link consisting of a vertical portion pivoted on one of said last parts and a portion which passes to the other last part, said last named link portion being connected to the vertical portion of the link attached to the other of said last parts below the point of their crossing each other.
5. In a last, a heel part, and a toe part so arranged as to pivot with respect to one another in moving from collapsed to expanded position and vice-versa, links connecting said parts, said links consisting of vertical portions pivoted on said last parts and portions which pass from one part to another and are connected to the opposite link below the point of their crossing each other, the points of pivoting said links being so located that a line drawn between

them will pass over the dead center when said last parts move from one position to the other.

6. In a last, a heel part, a toe part, means for pivoting said parts one on the other, links connecting said parts, means for mounting said links in said last parts and levers associated with said links to flex said links when the parts pass over dead center.

7. In a last, a heel part and a toe part of resilient material, means for pivoting said parts one on the other, links connecting said parts, levers connected with said links and means for mounting said links and levers in said parts, the parts being so arranged that the material between the points of connection of the links and levers to the last parts will be compressed when said parts pass over dead center.

In testimony whereof, I affix my signature.

GEORGE CLAUSING.
